COMB

Filed March 14, 1946

INVENTOR
LEWIS J. BIEL
BY
Howard Thompson
ATTORNEY

to and throughout the entire field of endeavor, including the use of the invention in the pocket or purse, a comb for combing the hair, and at the same time, to carry a file for trimming, cleaning or otherwise caring for the nails of the fingers of a hand, especially in sprucing up for any occasion.

Fig. 1 is a side view partly in section of a comb made according to my invention.

Fig. 2 is a plan view thereof; and

Fig. 3 is a partial section on the line 3—3 of Fig. 1, on an enlarged scale.

It has been the custom for men and women to carry in the pocket or purse, a comb for combing the hair, and at the same time, to carry a file for trimming, cleaning or otherwise caring for the nails of the fingers of a hand, especially in sprucing up for any occasion.

It is the purpose of my invention to provide in one device, an article serving both functions, thereby eliminating the need of carrying two independent articles, and further dispensing with the carrying of the objectionable article, namely the file, which is injurious, particularly to a pocket, and will invariably form a hole in the pocket.

In the accompanying drawing, I have shown an adaptation of my invention, and at 10 is shown a comb composed of rubber compositions, plastics and similar materials. At 11 is shown the elongated and preferably rounded back of the comb body, which back terminates in downwardly curved end portions 12 and 13. Between the end portions 12 and 13, and extending from the back 11, are a series of comb teeth 14, which may be of any desired structure, as in other devices of this type and kind.

The comb back 11 may be said to be longitudinally curved and has a more or less transversely rounded upper edge portion 15, which edge portion has within end limits of the back 11 a recess 16 in which is disposed a longitudinally curved file element 17, the cutter, teeth or edge 18 of which is preferably disposed within the normal rounded edge 15, and in fact, the upper edges of the side walls of the recess are slightly rounded,

allowing the 17 to be withdrawn from the recess 16, the cutter edge 18 being slightly rounded to conform to the rounded edge 15, so as to prevent injury to the fingers when the file 17 is withdrawn from the recess 16.

Fig. 2 illustrates the plan view of the back 11 of the comb, showing the rounded upper edge 15, the recess 16, the file 17, the cutter edge 18, and the rounded side walls of the recess 16.

Fig. 3 illustrates the partial section of the comb body 11, showing the teeth 14, the back 11, the rounded upper edge 15, the recess 16, the file 17, the cutter edge 18, and the rounded side walls of the recess 16.

Lewis J. Biel, Newton Highlands, Mass.

Application March 14, 1946, Serial No. 654,252

2 Claims. (Cl. 132—76.4)

1

This invention relates to combs, especially of the pocket type. More particularly, the invention deals with a comb structure wherein one end portion of the plastic or other material is extended to form a pointed fingernail cleaning and treating element. Still more particularly, the invention deals with a comb in which the heavy walled back member of the comb includes a file insert, preferably extending longitudinally of the outer curved edge of the back of the comb. The novel features of the invention will be best understood from the following description when taken together with the accompanying drawing, in which certain embodiments of the invention are disclosed, and in which the separate parts are designated by suitable reference characters in each of the views, and in which:

Fig. 1 is a side view partly in section of a comb made according to my invention.

Fig. 2 is a plan view thereof; and

Fig. 3 is a partial section on the line 3—3 of Fig. 1, on an enlarged scale.

It has been the custom for men and women to carry in the pocket or purse, a comb for combing the hair, and at the same time, to carry a file for trimming, cleaning or otherwise caring for the nails of the fingers of a hand, especially in sprucing up for any occasion.

It is the purpose of my invention to provide in one device, an article serving both functions, thereby eliminating the need of carrying two independent articles, and further dispensing with the carrying of the objectionable article, namely the file, which is injurious, particularly to a pocket, and will invariably form a hole in the pocket.

In the accompanying drawing, I have shown an adaptation of my invention, and at 10 is shown a comb composed of rubber compositions, plastics and similar materials. At 11 is shown the elongated and preferably rounded back of the comb body, which back terminates in downwardly curved end portions 12 and 13. Between the end portions 12 and 13, and extending from the back 11, are a series of comb teeth 14, which may be of any desired structure, as in other devices of this type and kind.

The comb back 11 may be said to be longitudinally curved and has a more or less transversely rounded upper edge portion 15, which edge portion has within end limits of the back 11 a recess 16 in which is disposed a longitudinally curved file element 17, the cutter, teeth or edge 18 of which is preferably disposed within the normal rounded edge 15, and in fact, the upper edges of the side walls of the recess are slightly rounded,

as seen at 19, so as to guide the nail of a finger to the cutter edge 18 of the file 17.

In production, the back 11 may be molded with the recess 16 therein, after which the file 17 may be cemented or otherwise secured in position. On the other hand, and as is known in the art, the file 17 may be formed as an insert in casting the comb body.

Extending integrally from the back 11 at the end 12, and also integral with said end 12 is a nail treating element 20, upper and lower edges 21 and 22 of which converge outwardly to form a more or less pointed end 23 and the side surfaces 24 and 25 of the element 20 are also converged to 15 the pointed end 23, as seen in Fig. 2 of the drawing.

The element 20 provides means for cleaning under the fingernails, and also means for removing free cuticles or in setting or otherwise trimming the cuticles, and this element in conjunction with the file 17, provides a simple and practical means for performing normal manicuring operations in preparing the hands, and simultaneously in the operation of combing the hair 25 on occasions for sprucing up, particularly before meal times.

By extending the element 20 outwardly beyond the end 12 of the comb, this element is free for performing the operations above indicated in a simple and effective manner. At the same time, this element will not in any way interfere with the normal use of the comb and in carrying the comb in the pocket, the end portion 13 being placed downwardly, thus preventing injury to the 35 pocket.

It will also be apparent that the protruding rounded edges 19 also form guards for the cutter edge 18 of the file 17 so that the file will not be injurious to the pocket in placing the comb in and 40 removing the same from the pocket. On the other hand, these protruding edges act as guides in directing the nails to the roughened or cutter surface 18 of the file. At the same time, the edges 19 provide guards which will prevent injury 45 to the fingers beneath the nail in the filing operation.

By conforming the cutter edge 18 to the longitudinally rounded back edge 15 of the comb, the file can be conveniently and practically used in trimming the fingernails, particularly in trimming side corner portions of the nails, as will be apparent.

It will also be noted from a consideration of Fig. 1 of the drawing that the outer edge of the 55 element 20 is formed continuous with the curved

edge 15 which keeps the element 20 well within the environment of the comb body especially with respect to the widest dimensions of the body.

Having fully described my invention, what I claim as new and desire to secure by Letters Patent is:

1. An article of manufacture comprising a bar-like portion having an elongated recess, the recess having side and end walls, a file embedded in said recess with the outer surface of the file arranged inwardly of said side and end walls of the recess, and said side walls being continuous between said end walls to provide a channel adapted to guide the nail of a finger over the file in trimming said nail.

2. An article of manufacture comprising a back member, said back member having an elongated recess intermediate its ends and opening through the outer edge of the back member, a nail trimming element mounted in and extending the full length of the recess of said back member and exposed through said edge of said member, said back member having finger guards extending

longitudinally and continuously of each side of and for the full length of said element and projecting outwardly beyond the exposed surface of said element, and the back member and said element being longitudinally curved.
